UNITED STATES PATENT OFFICE.

JOSEPH G. LA POINT, OF NEW ALBANY, INDIANA.

PNEUMATIC CUSHION FOR STUMP-LEGS.

1,057,562.

Specification of Letters Patent.

Patented Apr. 1, 1913.

Application filed June 21, 1911. Serial No. 634,614.

To all whom it may concern:

Be it known that I, JOSEPH G. LA POINT, a resident of New Albany, in the county of Floyd and State of Indiana, have invented

5 a new and Improved Pneumatic Cushion for Stump-Legs, of which the following is a full, clear, and exact description.

The object of the invention is to provide a simple and effective cushion for a stump 10 leg to support it easily within the shell and against the upper edge of the shell of the artificial leg.

The invention consists of novel features 15 and parts and combinations of the same, which will be more fully described herein-after and then pointed out in the claim.

A practical embodiment of the invention is represented in the accompanying drawings, 20 forming a part of this specification, in which similar characters of reference indicate corresponding parts in all the views.

Figure 1 is a vertical section showing the shell and the cushion in position on the 25 stump leg; Fig. 2 is a perspective view of the stump leg and cushion wrapped thereon before it has been covered by the outer stump sock; and Fig. 3 is a perspective view of a modification of the pneumatic cushion.

30 A stump leg is ordinarily supported several inches above its end against the inner wall and the upper edge of the shell of the artificial leg. Heretofore pneumatic coils have been used within the shell to support the 35 stump therein, and a specially placed pneumatic coil has been used to support the stump against the upper edge of the shell. This arrangement is very expensive, causes undue pressure against the stump at the upper 40 edge of the shell, and requires two different pieces, specially arranged, to give the support in both places.

An ordinary pneumatic bladder, in the form of a sleeve will not produce the desired results, because it is too easily displaced lengthwise.

By using a pneumatic sleeve 3, provided with a valve 4 to support the stump 1 against the shell 5, in which the outer wall, or both walls, is made of rubberized silk or other stiffened non-elastic, flexible, air-tight material, I provide a pneumatic cushion in which the air will not be all pushed outside the shell and which will form a widened ring, as shown in Fig. 1, to support the 55 stump against the upper edge of the shell and hold it securely in place vertically.

The pneumatic cushion 3 should be placed on the stump outside an inner stump sock 2 and should be covered by an outer stump 60 sock 6 as shown in Fig. 1.

In the preferred form of my invention I split the cushion 3 lengthwise, as shown in Fig. 2, so that it can be wrapped around the stump like a bandage after it is inflated. 65 The cushion may also be made with its walls in the form of a portion of a conical surface as shown in Fig. 3.

I do not limit myself to the exact form in which my invention is herein disclosed further than is indicated in the claim which 70 follows.

I claim:

A pneumatic stump support consisting of 75 a rectangular inflatable cushion of greater length than the circumference of the leg, so that it may be overlapped, said cushion being extended over and resting upon the upper edge of the leg socket and furnished with a valve at its upper edge.

JOSEPH G. LA POINT.
